CONTROL SYSTEM FOR VAPOR-ELECTRIC VALVES

Joseph H. Cox, Forest Hills, and Henry C. Myers, Irwin, Pa., assignors to Westinghouse Electric & Manufacturing Company, East Pittsburgh, Pa., a corporation of Pennsylvania

Application November 26, 1941, Serial No. 420,532

4 Claims. (Cl. 175—354)

Our invention relates to a vapor-electric device and particularly to a control system for securing control of the device with a minimum expenditure of control energy.

In the development of make-alive type valves, it has been found that the rating of the valves can be materially increased by providing an anode shield about the anode for rapidly deionizing the anode space. However, when such an anode shield is utilized, it has been found desirable to apply excitation potential to the anode shield to insure rapid pick-up of the current-carrying arc to the anode.

The application of potential to the anode shield requires the use of a greater amount of control energy in energizing the tube. However, it is very desirable that the application of control potential to the make-alive electrode should terminate as soon as possible after the formation of the cathode spot as is possible in order to conserve energy applied to the make-alive electrode and also reduce the heating and possible erosion of the make-alive electrode by the excessive current.

According to our invention, we not only secure the termination of the make-alive energy but also conserve the energy otherwise utilized in energizing the anode shields by energizing both the make-alive electrode and the anode shield from the same source of control potential and supplying means whereby the make-alive energy ceases to flow to the make-alive electrode upon the formation of the cathode spot and the flow of current to the anode shield. We accomplish this result by providing an impedance in series with the make-alive electrode and connecting the anode shield in parallel with the make-alive electrode and its associated impedance. Therefore, when the cathode spot is formed, an excitation arc will pick up from the anode shield short circuiting the flow of energy to the make-alive electrode.

It is accordingly an object of our invention to provide a control system wherein a single source supplies energy to both the make-alive electrode and the anode shield.

It is a further object of our invention to provide a control system in which the flow of energy to the anode shield will relieve the duty on the make-alive electrode.

Other objects and advantages of our invention will be apparent from the following detailed description, taken in conjunction with the accompanying drawing, in which the single figure is a schematic illustration of a vapor-elec- 55

tric conversion system according to our invention.

In the illustrative embodiment of our invention, the polyphase alternating current circuit 5 10 is connected to a direct current circuit 11 by means of a rectifier transformer 12. A suitable disconnecting switch 52 is placed between the alternating current circuit 10 and the primary winding 13 of the rectifier transformer 12. The direct current circuit 11 is preferably provided with a disconnecting switch 12 which may be of the high-speed reverse-current or so-called "bucking-bar" type. The valve phase terminals 1 to 6 of the secondary winding 14 of the transformer 12 are connected to the anodes 1a to 6a of the make-alive type valves 15, which control the flow of energy between the circuits 10 and 11.

Each of the make-alive type valves 15 comprises a vaporizable reconstructing cathode 16 usually of mercury or other metal which is liquid at the operating temperatures of the valves. Co-operating with the cathode 16 is one of the anodes 1a—6a spaced from and insulated from the cathode 16. The anodes are usually surrounded by a suitable shield 17 usually in the form of a graphite basket which serves to deionize the space immediately adjacent to the anode and thus improve the commutating characteristics of the valve. The initiation of the current spot is obtained by a make-alive electrode 18, a portion of which is in permanent contact with the cathode 16 during normal operation of the device. All of these elements are preferably contained in a suitable evacuated chamber or container 19.

The application of control potentials to the various make-alive electrodes 18 and the anode shields 19 is supplied by a control circuit presently to be described. The preferred control circuit comprises a source of polyphase alternating current having the same frequency as the potential applied to the rectifier transformer 12. For convenience, we have shown this potential as being derived directly from the alternating current circuit 10.

Any suitable impulsive device energized from the control current source may be utilized for supplying impulses to the make-alive electrodes, we prefer to utilize a wave distorting circuit embodying a saturable core reactor for controlling the wave-shape applied to the make alive electrodes 18.

For purposes of illustration, we have disclosed the rectifier transformer secondary 14 as being of the double three-phase type in which pairs of

valves, such as 1 and 4, 3 and 5, 2 and 6, have valves which are alternately energized during normal operation of the device. In order to make full use of the wave distorting circuits, we provide an excitation transformer 20 having a plurality of secondary windings 21 electrically insulated from each other and corresponding in number to the pairs of valves as energized by the main transformer 12. Each of the secondary windings 21 has associated with it a wave distorting circuit comprising a substantially linear impedance 22 connected in series with the winding 21, a capacitor 23 connected in shunt across the winding 21 and the linear impedance 22 so that the capacitor 23 is charged through the linear impedance 22 then when the potential of the winding 21 reaches a value sufficient to supply saturating current to the saturable reactor 24 connected in series with the linear reactor the capacitor discharges through the saturable reactor and assists in producing a high peak of current with the minimum capacity of transformer 20. The opposite terminals of this wave distorting network are connected to the respective make-alive electrodes 18 of a pair of valves by means of a series rectifier or asymmetrical connector 25. A suitable return circuit is provided by connecting a second asymmetrical conductor 26 in shunt with each make-alive electrode 18 and its associated series rectifier 25.

The connection and phase relation of the impulsive transformer 20 is selected to produce the make-alive control impulse at substantially the desired instant in the make-alive type valves. However, it is desirable to provide a phase shifter such as the induction phase shifter 30 to correctly determine the phase position or to change the phase position of the make-alive impulses.

In the operation of this system, the potential of the winding 21 flows through the impedance 22 charging the capacitor 23 until the potential required to saturate the core of the saturable reactor 24 at which time a pulse of current will flow through the reactor and, depending upon the polarity, will be selectively applied to the proper make-alive electrode 18 by the series shunt rectifiers 25-26. The reversal of polarity of the secondary winding 21 will produce an impulse of the opposite polarity which will then fire the alternate valve of the connected pair. However, it is desirable to relieve the make-alive electrode 18 of all excess current flow after the cathode spot has been formed. We accomplish this by a connection 31 intermediate the series shunt rectifiers 25-26 to the anode shield 17. With this connection, as soon as the make-alive current has initiated a cathode spot, current will flow to the anode shield 17 and establish an excitation arc between the cathode 16 and shield 17. Because of the impedance of the make-alive electrode 18 and its series asymmetric conductor 25, the major portion of the current will appear in the keep-alive excitation. However, if it is found that too large a current still flows through the make-alive electrode 18, a suitable impedance 32 may be placed in series with the make-alive electrode 18, preferably between the make-alive electrode 18 and its series connected asymmetric conductor 25 in order to increase the current flowing to the anode shield 17.

As will be obvious from an inspection of the drawing, the current flowing through a make-alive electrode 18 flows through the cathode 16 and back to the opposite side of the wave dis-

torter circuit through one of the shunt asymmetric conductors 26. The series shunt asymmetric conductors 25-26 provide a circuit in which two asymmetric conductors are connected in conducting relation from the cathode 16 to the make-alive electrode 18 and in which the controlled impulses are impressed intermediate the asymmetric conductors 25-26, the connection 31 for the relieving anode 17 being conveniently made also at the same point intermediate the asymmetric conductors at which the wave distorting circuit is connected.

While for purposes of description we have shown and described a specific embodiment of our invention, it will be apparent that changes and modifications can be made therein without departing from the true spirit of our invention or the scope of the appended claims.

We claim as our invention:

1. In combination, an electric current translating system for transferring current between a polyphase alternating current circuit and a direct current circuit including a plurality of pairs of vapor-electric valves of the make-alive type, the valves of each pair being alternately conducting, each of said valves including a vaporizable reconstructing cathode, an anode, a make-alive electrode and an anode shield in an evacuated container, a control circuit comprising a source of polyphase alternating current of the same frequency as the alternating current circuit, means for producing a plurality of electrically insulated phase windings corresponding to the pairs of vapor-electric valves, an impulsive circuit energized by each phase winding, two asymmetric conductors connected in series conductive relation from each cathode to its associated make-alive electrode, connections from the impulsive circuit to a point intermediate the asymmetric conductors of a pair of valves and connections from the impulsive circuit to the anode shields of said pair of valves.

2. In an electric translating system using a plurality of vapor-electric valves of the make-alive type each valve including a cathode, an anode, an anode shield and a make-alive electrode, a control system comprising a source of control potential, means energized from said source for producing control impulses having an effective value of potential over a period less than a half cycle of the control potential, connections including an asymmetric conductor in series with the make-alive electrode and a second asymmetric conductor in shunt with the make-alive electrode and the first asymmetric conductor for selectively impressing the impulses on the make-alive electrode and a connection independent of said asymmetric conductors for impressing the control impulses on the anode shield.

3. In combination an electric current converter having a plurality of vapor-electric valves of the make-alive type, each valve including a cathode, a make-alive electrode in contact with said cathode, an anode in spaced insulated relation to said cathode, and an anode shield about the anode, a control system comprising a source of polyphase control potential, means for providing a plurality of substantially independent phase windings, a wave distorting circuit associated with each phase winding, means including said wave distorting circuits and a plurality of asymmetric conductors for selectively impressing the output of said phase windings on said make-alive electrodes and a connection intermediate said asymmetric conductors for impressing the potential

of said windings as modified by said wave dis-
torter circuit on the anode shield.

4. A control system for a vapor-electric valve
having an anode, a cathode, a make-alive elec-
trode and an anode shield comprising, a source
of alternating control potential, means for pro-
ducing from said source control impulses having
an effective value of potential for a minor por-
tion of each half cycle, connections including an

asymmetric conductor in series with the make-
alive electrode, a second asymmetric conductor in
shunt with said first-mentioned asymmetric con-
ductor and said make-alive electrode and a con-
nection from a point intermediate said asym-
metric conductors to said anode shield.
